UNITED STATES PATENT OFFICE.

JOHN H. LINDSAY, OF BUFFALO, NEW YORK.

DESIGN FOR A PORTABLE STATIONERY-HOLDER.

46,984.

Specification for Design.

Patented Feb. 16, 1915.

Application filed March 20, 1913. Serial No. 755,804. Term of patent 7 years.

To all whom it may concern:

Be it known that I, JOHN H. LINDSAY, a citizen of the United States, residing at Buffalo, in the county of Erie and State of New York, have invented a new, original, and ornamental Design for Portable Stationery-Holders, of which the following is a specification.

The accompanying drawing illustrates, by

a perspective view, a portable stationery holder embodying the design.

I claim:

The ornamental design for a portable stationery holder, as shown.

JOHN H. LINDSAY.

Witnesses:

C. W. PARKER,
A. L. McGEE.
